SPINNING FRAME

Charles Morton, Pawtucket, R. I.

Application April 22, 1931. Serial No. 531,868

15 Claims. (Cl. 19—135)

This invention relates to a spinning frame, more particularly to the tensioning of the rolls of the same, and has for its object to provide an arrangement whereby the upper roll of the back 5 pair of rolls may be tensioned by a suspending weight.

Another object of the invention is a provision of tensioning means which will permit ready access to the intermediate roll for removal thereof 10 when desired.

Another object of the invention is a provision of a tensioning means by which the rolls may be run with their axes in close adjacency for long draft spinning.

15 A further object of the invention is the arrangement of tensioning means for the upper roll of the back pair of rolls which will act upon one, two or more back rolls of this group at the same time.

20 A still further object of the invention is the provision of means whereby a weight acting upon back rolls of two or more groups may be disconnected from the back roll of one of said groups and still function on the back roll of the other 25 group.

With these and other objects and advantageous features in view, the invention consists of a novel arrangement of parts more fully disclosed in the detailed description following, in conjunction 30 with the accompanying drawings, and more particularly set forth in the appended claims.

Fig. 1 is a sectional view through the spinning frames with a common weighting means extending between the back and front rolls of the units.

35 Fig. 2 is a section taken on line 2—2 of Fig. 1.

Fig. 3 is a top plane view of a fragmental portion of one unit of the spinning frame at substantially line 3—3 of Fig. 1 showing the connection of the hanger for the weights to the rolls.

40 Fig. 4 is a perspective view of the hanger for the weight for the back pairs of rolls.

Fig. 5 is a perspective view of one of the weights.

Patents on my previous invention for spinning frames have illustrated means for tensioning the 45 rolls.

In Patent No. 1,783,301 a rod extends through the rolls and is tensioned by leverage and weight connection thereto. This patent also discloses tensioning the back draft breaker roll by increasing the weight of the roll as by enlarging

50 the diameter, while in Patent No. 1,721,028, dated July 16, 1929, I tension by supplying an additional roll or weight resting upon and having rolling contact with the surface of one of the rolls to be tensioned. Each of these different types of

55 tensioning which are disclosed in my prior pat-

ents have certain disadvantages. The rod extending through the rolls and operating upon a saddle engaging the front and back rolls prevents access to the intermediate roll and must be removed in order to permit removal of the intermediate roll, also frequently, the use of this construction causes damage to the surface of one of the rolls. The enlargement of the roll itself prevents moving the axes of the rolls closely together for long draft purposes, which is also an 60 objection to the use of an additional weight roll engaging the surface of one of the rolls. In order to avoid all these disadvantages, I have arranged to suspend a weight from both the upper roll of the front pair and the upper roll of the back 70 pair of each group of rolls, and have staggered the weights of the front and back pair to permit of such weighting; and the following is a detailed description of the present embodiment of this invention illustrating the preferred means by which 75 these advantageous results may be accomplished.

With reference to the drawings, 10 designates a supporting structure of a spinning frame, upon which identical units 11 and 12 are mounted back to back by means of pedestals 13 and 14. As each 80

of the units is identical a description of one will suffice for both. Draft rolls are provided consisting of front pairs of rolls 15 and 16, intermediate pairs of rolls 17 and 18, and back pairs of rolls 19 and 20. There is also provided on 85

each frame breaker draft rolls, the lower of which is designated 21 and the upper 22. The lower draft rolls are the driven rolls and a shaft of some length is provided with fluted or corrugated portions 23 at spaced intervals along its 90

length with portions 24 of lesser diameter therebetween. The upper draft rolls are each of a length to extend over two corrugated portions of the lower roll and are provided with a reduced portion 25 registering with the portion 24 of the 95 lower roll. (See Fig. 2.) The bearings 26 for the upper rolls are arranged over alternate portions 24 of the lower roll.

Although the reference characters designate portions of the back pair of rolls it will be understood that the intermediate 100 and front pairs of rolls are similarly constructed and arranged. Thus the upper rolls are arranged in groups of separate upper rolls each accommodating two strands of yarn or roving. Which groups I will designate in Fig. 3 for convenience 105

as A and B. To tension the rolls I apply pressure on the upper rolls. A hanger 27 is suspended from the reduced portion of each of the front rolls, and a weight 28 extending between the two units is attached to the hangers 27 by means of 110

the links 29 and thus pressure is applied to the upper rolls of the units by a weight 28 common to both. In a similar manner the upper roll of the front pair of rolls of the next group are 5 tensioned and so on.

To tension the back rolls of the spinning units, hangers 30 are connected to the upper roll of the back pair of each of the two groups of rolls A and B by engagement with the reduced portion 10 thereof. A yoke 31 connects the hangers of groups A and B, and from each of these yokes, hooks 32 depend to receive the weight 33 extending between the two for applying pressure to the back rolls of each of two groups of back rolls. 15 on each of the spinning units. By this arrangement I stagger the weights 28 and 33 with reference to each other so that one will not interfere with the other even though substantially in the same horizontal plane.

20 Should I desire to remove the back roll of the frame 11, I may lift one of the hangers 30 from place and rest one end of the yoke 31 in a notch 34 provided in the block 35 on the support 10 without displacing the other hanger 30 on the 25 next group of rolls and thus permitting them to run and be weighted through its hanger 30, yoke 31 supported in the notch 34, link 32 and weight 33.

By this arrangement the rolls may be of small 30 diameter and run with their surfaces in close adjacency for long draft and the intermediate roll 17 may be removed without displacing the tensioning means.

The foregoing description is directed solely 35 towards the construction illustrated, but I desire it to be understood that I reserve the privilege of resorting to all the mechanical changes to which the device is susceptible, the invention being defined and limited only by the terms of the 40 appended claims.

I claim:

1. In a spinning frame groups of aligned front and back pairs of draft rolls, independent means below said frame elongated in a horizontal plane 45 and at right angles to the axis of said rolls for weighting the upper rolls of each front pair of rolls and means independent of the front weighting means and located between two front weighting means and below the frame for weighting the 50 upper rolls of the back pairs of draft rolls.

2. In a spinning frame groups of aligned front and back pairs of draft rolls, independent means below said frame and extending at right angles to the axis of said rolls for weighting the upper 55 rolls of each front pair of rolls and means independent of the front weighting means and located between two front weighting means and parallel thereto and below the frame, and means for distributing its weight between the upper rolls 60 of two pairs of co-axial draft rolls.

3. In a spinning frame groups of aligned front and back pairs of draft rolls, independent means below said frame for weighting the upper rolls 65 of each front pair of rolls, a yoke, means for connecting said yoke to two pairs of back rolls and a weight suspended from said yoke for weighting said back rolls.

4. In a spinning frame groups of aligned front and back pairs of draft rolls, independent means 70 below said frame for weighting the upper rolls of each front pair of rolls, a yoke, means for connecting said yoke to two pairs of back rolls and a weight suspended from said yoke and located between the weighting means for the upper 75 pairs of front rolls.

5. In combination a pair of spinning units, each having groups of aligned front and back pairs of draft rolls, common weighting means for applying pressure to the upper rolls of a pair of front rolls on each spinning unit and weighting means in a vertical plane spaced from the plane of said common weighting means for applying pressure to the upper roll of a pair of back rolls on each spinning unit. 80

6. In combination a pair of spinning units each having groups of aligned front and back pairs of draft rolls, common weighting means for applying pressure to the upper rolls of a pair of front rolls on each spinning unit and a yoke, means for connecting said yoke to the pair of back rolls on each frame and a common weight extending between said yokes for weighting said back rolls. 90

7. In a spinning frame groups of aligned front and back pairs of draft rolls, independent means below said frame for weighting the upper rolls of each front pair of rolls, a yoke, means for connecting said yoke to two pairs of back rolls and a weight suspended from said yoke for tensioning said back rolls, and means for receiving one end of the yoke to support it when disconnected from its connection to one of the back rolls. 95

8. In a spinning frame groups of aligned front and back pairs of draft rolls, independent means below said frame for weighting the upper rolls of each front pair of rolls, a yoke, means for connecting said yoke to two pairs of back rolls and a weight suspended from said yoke for tensioning said back rolls, and a notched block mounted on the frame for receiving one end of the yoke to support it when disconnected from the back roll whereby the other group of rolls to which it is connected may continue to function. 100

9. In combination a pair of spinning units, each having groups of aligned front and back pairs of draft rolls, a hanger depending from each pair of front and back rolls, a weight connected to each hanger of the front rolls and extending between two hangers from different units, a yoke connecting each pair of hangers from the back rolls and a weight connected to each yoke and extending between two yokes one on each unit and located between the weights of the front rolls and in substantially the same horizontal plane. 110

10. In combination, a pair of spinning units, each having groups of aligned front and back pairs of draft rolls, independent common weighting means located below the frame for applying pressure to the upper roll of each front pair of rolls of each unit, and means independent of the front weighting means and located between the front weighting means and below the frame for applying pressure on the upper roll of the back pair of rolls of each unit, the axes of said weighting means being parallel and at right angles to the axis of said rolls. 120

11. In combination, a pair of spinning units, each having groups of aligned front and back pairs of draft rolls, common weighting means for applying pressure to the upper rolls of a pair of front rolls on each spinning unit, and means independent of the front weighting means located in the horizontal plane with and between the weighting means for the front rolls and below the frames for applying pressure to the upper rolls of the back pairs of draft rolls on each spinning unit. 130

12. In a spinning frame, groups of aligned front and back pairs of draft rolls, independent weighting means below said frame elongated in a 145
